UNITED STATES PATENT OFFICE.

JOHN G. MUELLER, OF DAYTON, OHIO.

RAILWAY BRACE.

Application filed March 22, 1923. Serial No. 626,966.

To all whom it may concern:

Be it known that I, JOHN G. MUELLER, a citizen of the United States, residing at Dayton, in the county of Montgomery and 5 State of Ohio, have invented certain new and useful Improvements in Railway Braces, of which the following is a specification, reference being had therein to the accompanying drawing.

10 This invention relates to improvements in railway braces.

The object of the invention is to brace the ball of the rail by adjustable brace members combined with other members which 15 in one form embrace the base of the rail and in a modified form embrace both the web and the base of the rail.

In the accompanying drawings:—

Fig. 1 is a view showing my invention 20 applied to a railway rail, the rail and parts of the braces being in section and the remainder of the braces in elevation;

Fig. 1^a is a section taken on the line 1^a—1^a of Fig. 1.

25 Fig. 2 is a like view showing a modified form in which the inner brace grips the web as also the base of the rail.

Fig. 2^a is a section taken on the line 2^a—2^a of Fig. 2.

30 Referring to the drawings the numeral 1 designates a railway rail of any of the kinds in general use, the numeral 2 indicates my outer brace having a contact part 3 to engage with the ball of the rail and a contact 35 part 4 which impinges against the upper part of the web. This outer brace is bored out at 5 to receive the tie bolt or rod 6 having nuts 7 and washers 8. By manipulating these nuts against the washers the upper 40 ends of the outer braces are set firmly against the rail ball and rail web. Their lower ends 9 extend below the tie bolt and impinge at the point 10 against the upper inclined surfaces of the filler blocks 11 which 45 also are bored out to receive the tie bolt and at their upper ends form a chair or seat 12 for the base of the rail. Ledges 13 on the chair embrace the edges of the rail base. To further bind the rail by contact with the 50 upper faces of its base I provide inner braces 14 which lie between the outer braces and the upper faces of the rail base and at the point 15 bear against the filler blocks and cooperate with them in gripping the rail 55 base. These inner braces are bored out to receive the tie bolt and in their substantially

vertical portions are fitted to occupy grooves 16 in the adjacent parts of the outer braces.

Referring to the modification shown in Fig. 2 it will be seen that the inner braces 14^a have portions 15^a which extend to and against the rail web, while these braces also contact with the upper surface of the rail base at the point 16^a and with the lower surface at 17^a of the filler block 11^a, which in this case comprises one member instead of two, as in Fig. 1. And in this modified form the filler block has a portion 12^a which extends downward and is bored out to receive the tie bolt 6. The filler block constitutes a chair for the rail base, as indicated at 13^a, and has ledges 18^a to embrace the edge of the rail base.

Referring again to the inner braces 14^a in this modified form it will be seen that they extend down and have portions 19^a for contact with the surface 10 of the outer braces, just as in the form shown in Fig. 1. But the grooves 20^a in the outer braces are located not in the vertical portion as in Fig. 1 but along the curved part of the inner face to receive the web 21^a of each inner brace.

It will now be seen that in the form shown in Fig. 1 when one or both of the nuts on the tie rods are screwed up and exert pressure against the outer braces the effect is to cause the outer braces, the inner braces and the filler block all to clamp and rigidly hold the rail.

And it will be seen also that in the modified form shown in Fig. 2 when one or more of the nuts on the tie bolt are screwed up to exert pressure on the outer braces, both outer braces, both inner braces and the single chair seat will be forcibly clamped against the rail.

The result in both cases is a firm and certain holding of the rail against movement in all directions which the weight and force of trains travelling over it will tend to provide.

Having thus fully described my invention, what I claim as new and desire to secure by Letters Patent, is:—

1. In a railway rail brace, the combination with outer braces, inner braces and a filler block, the outer braces adapted to clamp a rail ball and to force the inner braces against the filler block to cause them to grip the rail base, of a tie bolt adapted to extend through the outer braces and provided with devices for exerting pressure

against the outer braces to produce the clamping action stated.

2. In a railway rail brace, the combination with outer braces, inner braces, and a 5 filler block, the outer braces being adapted to brace a rail ball to exert pressure on the inner braces to cause them to grip the upper face of a rail base, and the inner braces adapted to exert pressure on the filler block 10 to cause it to grip other parts of the rail base, of a tie bolt extending through the outer braces and having devices adapted to exert pressure against the outer braces to effect the result stated.

15 3. In a railway rail brace, the combination with outer braces having upper portions adapted to embrace a rail ball and lower portions with an inclined surface, inner braces fitted against upper portions of 20 the outer braces and against the upper surfaces of the rail base, and a filler block having portions which form a chair for the rail base, other portions which contact with the

inner braces and still other portions which contact with the lower part of the outer 25 braces, of a tie bolt which extends through said braces and filler block and is provided with devices to exert a clamping action against the outer braces to effect the results stated.

4. In a railway rail brace, the combination with a pair of outer braces having inclined upper and vertical lower members, a pair of inner braces slidably fitted against the outer braces and adapted by their upper 35 portions to contact with the rail web and upper surface of the rail base, and a filler block constituting a chair for the rail base in slidable contact with other portions of the inner braces, of a tie rod which passes 40 through the braces and has adjusting nuts by which both pairs of braces are adjusted and likewise the chair block.

In testimony whereof, I affix my signature.

JOHN G. MUELLER.
